DETACHABLE BIT ROCK DRILL

Gustave Knutson, South Porcupine, Ontario, Canada, assignor, by mesne assignments, to International Detachable Bits & Equipment, Limited, Timmins, Ontario, Canada, a corporation of Ontario, Canada

Application March 31, 1938, Serial No. 199,200

10 Claims. (Cl. 255—64)

My invention relates to improvements in detachable bit rock drills particularly of the type wherein the connection between bit and shank comprises a dovetail tongue on one member insertable into a dovetail slot in the other member, and an object of the invention is to devise an improved form of dovetail connection between bit and shank which will tend to retain the bit in axial alignment with the shank during drilling and obviate the liability of its being deflected from its course due to slips and other changes in rock formation.

A further object of the invention is the provision of means on the dovetail tongue engageable with an abutment in the dovetail slot for further assisting in keeping the bit in axial alignment with the shank as it can only be detached from such shank from the side from which it has been inserted.

With the above and other objects in view which will hereinafter appear as the specification proceeds my invention, in its preferred embodiment, consists of the construction all as hereinafter more particularly described and illustrated in the accompanying drawing in which:

Fig. 1 is a side view of a rock drill constructed according to my invention.

Fig. 2 is a similar view taken at right angles to Fig. 1.

Fig. 3 is a side view (partly in section) showing the detachable bit partially inserted into or detached from the shank.

Fig. 4 is a vertical section of the shank taken on the line 4—4 (Fig. 5).

Fig. 5 is a plan view of the shank, and

Figs. 6 and 7 are side views of the detachable bit taken at right angles to each other.

Like characters of reference indicate corresponding parts in the different views of the drawing.

Hitherto it has been the practice in dovetail connections between bit and shank to have the dovetail slot and dovetail tongue extend straight across shank and bit respectively at substantially right angles to their axes. The disadvantage of such construction is that the dovetail tongue, being laterally movable in the dovetail slot, tends to permit the bit to get out of axial alignment with the shank during drilling and to be deflected from its course.

According to my invention, I obviate this disadvantage by making the dovetail tongue substantially arcuate in longitudinal vertical section and the dovetail slot also correspondingly arcuate in the same section. Consequently, when the bit

is applied to the shank in axial alignment and the drill inserted into a hole in the rock which may have been previously begun by a starter drill or other drill, the axes of bit and shank will remain substantially coincident as the bit cannot slide sidewise relatively to the shank unless its axis is disposed angularly to the shank. Such angularity is obviously prevented by the wall of the hole being drilled.

Referring to the specific construction of my invention as illustrated in the drawing, the shank 1 provided with the usual axial water orifice 2 therethrough has a cupped bit engaging end 3 with a diametrical slot 4 of dovetail cross-section extending thereacross. Such slot is arcuate in longitudinal vertical section conforming with the curvature of the cupped end 3. Arcuate grooves 5 and 6 are provided respectively in each side wall of the slot 4 in the vicinity of its arcuate roof and such grooves are opposingly positioned in the side walls of the slot so as to extend from their ends to substantially a mid-point in their length.

The detachable bit 7 provided with cutters 8 and an axial water orifice 9 has a domed upper portion 10 corresponding to the cupped end 3 of the shank into which it is adapted to be received and a diametrically extending tongue 11 of dovetail cross-section corresponding to that of the dovetail slot 4 in the shank surmounts the domed upper portion 10 of the bit, such tongue being arcuate in longitudinal vertical section corresponding with the curvature of the slot 4 in the shank. A projection 12 is provided on a side wall of the tongue 11 at its mid-point and is receivable into a groove 5 or 6 in the walls of the slot 4 when the bit is applied to the shank.

In applying the bit to the shank, its axis is disposed at an angle to the axis of the shank as illustrated in Fig. 3 and the end of the tongue 11 is inserted into the slot 4. Simultaneously the projection 12 is inserted into the groove 5 or 6 depending from which side of the shank the tongue is introduced. Then by sliding the bit laterally, the tongue 11 follows the slot 4 until the axis of the bit becomes coincident with the axis of the shank. In such position the projection 12 abuts against the end of the groove 5 or 6 and further movement of the bit in such direction is prevented. The bit can now only be moved in 50 a reverse direction to the direction in which it has been inserted in the shank.

The cupped end 3 of the shank 1 abuts the domed portion 10 of the bit and consequently a rigid detachable connection between bit and shank is constituted.

From the above description it will be apparent that I have devised a detachable bit drill in which the dovetail connection between bit and shank is such that in drilling, lateral movement of the former relatively to the latter is obviated by the provision of the arcuate tongue and arcuate slot assisted by the projection on the tongue abutting the end of a groove in one side wall of the arcuate slot.

Although I have illustrated and described the arcuate tongue as being on the bit and the arcuate slot in the end of the shank these elements may, if desired, be reversed.

What I claim as my invention is:

1. In a detachable bit rock drill, the combination with a shank member and detachable bit member, of a detachable connection between bit and shank members comprising a diametrical tongue of dovetail cross-section and arcuate in longitudinal vertical section on the end of one of the members receivable into a correspondingly shaped slot in the end of the other member.

2. In a detachable bit rock drill, the combination with a shank member and detachable bit member, of a detachable connection between bit and shank members comprising a diametrical tongue of dovetail cross-section and arcuate in longitudinal vertical section on the end of one of the members receivable into a correspondingly shaped slot in the end of the other member, and coacting means between tongue and slot for preventing the tongue being inserted into the slot further than a position in which the axes of bit and shank are coincident.

3. In a detachable bit rock drill, the combination with a shank member and detachable bit member, of a detachable connection between bit and shank members comprising a diametrical tongue of dovetail cross-section and arcuate in longitudinal vertical section on the end of one of the members receivable into a correspondingly shaped slot in the end of the other member, and a projection on a side wall of the tongue insertable into an arcuate groove in a side wall of the slot, said groove terminating at a mid-point in the length of the slot.

4. A detachable bit rock drill comprising a shank having a diametrical slot of dovetail cross-section in its bit engaging end, said slot being arcuate in longitudinal vertical section, and a detachable bit having a diametrical tongue of dovetail cross-section on its shank engaging end, said tongue being arcuate in longitudinal vertical section corresponding to the curvature of the slot into which it is inserted.

5. A detachable bit rock drill comprising a shank having a diametrical slot of dovetail cross-section in its bit engaging end, said slot being arcuate in longitudinal vertical section, and a detachable bit having a diametrical tongue of dovetail cross-section on its shank engaging end, said tongue being arcuate in longitudinal vertical section corresponding to the curvature of the slot into which it is inserted, and coacting means be-

tween bit and shank for preventing the insertion of the tongue into the slot past a position in which the axes of bit and shank are coincident.

6. A detachable bit rock drill comprising a shank having a diametrical slot of dovetail cross-section in its bit engaging end, said slot being arcuate in longitudinal vertical section, a detachable bit having a diametrical tongue of dovetail cross-section on its shank engaging end, said tongue being arcuate in longitudinal vertical section corresponding to the curvature of the slot into which it is inserted, and a projection on a side wall of the tongue insertable in an arcuate groove in a side wall of the slot, said groove terminating at a mid-point in the length of the slot.

7. A detachable bit rock drill comprising a shank with a cupped bit engaging end and a diametrical slot of arcuate cross-section in such end, said slot being arcuate in longitudinal vertical section, a detachable bit having a domed portion receivable into the cupped end of the shank, and a diametrical tongue of dovetail cross-section and arcuate in longitudinal vertical section corresponding to the curvature of the slot in the shank into which it is receivable.

8. A detachable bit rock drill comprising a shank with a cupped bit engaging end and a diametrical slot of arcuate cross-section in such end, said slot being arcuate in longitudinal vertical section, a detachable bit having a domed portion receivable into the cupped end of the shank, and a diametrical tongue of dovetail cross-section and arcuate in longitudinal vertical section corresponding to the curvature of the slot in the shank into which it is receivable, and coacting means between bit and shank for preventing the insertion of the tongue into the slot past a position in which the axes of bit and shank are coincident.

9. A detachable bit rock drill comprising a shank with a cupped bit engaging end and a diametrical slot of arcuate cross-section in such end, said slot being arcuate in longitudinal vertical section, a detachable bit having a domed portion receivable into the cupped end of the shank, a diametrical tongue of dovetail cross-section and arcuate in longitudinal vertical section corresponding to the curvature of the slot in the shank into which it is receivable, and a projection on a side wall of the tongue insertable in an arcuate groove in a side wall of the slot, said groove terminating at a mid-point in the length of the slot.

10. In a rock-drilling combination, a shank member having a concave end portion curved on a radius having a center on the axis of said shank and provided with a diametrical dovetail slot curved on a radius having a center coinciding with said first named center, and a bit member having an end portion and diametrical dovetail portion curved complementally to, and adapted to engage, respectively, said curved shank end and dovetail slot.

GUSTAVE KNUTSON.
